UNITED STATES PATENT OFFICE.

VICTOR WILLOUGHBY, OF JEFFERSONVILLE, INDIANA, ASSIGNOR TO AMERICAN CAR AND FOUNDRY COMPANY OF ST. LOUIS, MISSOURI, A CORPORATION OF NEW JERSEY.

MAIL-POUCH RACK.

1,052,781.

Specification of Letters Patent. Patented Feb. 11, 1913.

Application filed December 11, 1911. Serial No. 665,127.

To all whom it may concern:

Be it known that I, VICTOR WILLOUGHBY, residing at Jeffersonville, Clark county, Indiana, and being a citizen of the United States, have invented certain new and useful Improvements in Mail-Pouch Racks, of which the following is a full, clear, and exact description, such as will enable others skilled in the art to which it appertains to make and to use the same, reference being had to the accompanying drawings, which illustrate the preferred forms of the invention, though it is to be understood that the invention is not limited to the exact details of construction shown and described, as it is obvious that various modifications thereof will occur to persons skilled in the art.

In said drawings: Figure 1 is a side elevational view of my improved pouch rack, showing the same in full lines when in position for use and in dotted lines when folded up and not in use, Fig. 2 is a front elevational view of the rack extended as when in use, Fig. 3 is a similar view of the rack closed, as shown in dotted lines in Fig. 1, Fig. 4 is a perspective view of two of the frame members detached, Fig. 5 is a perspective view of a pair of adjoining brackets, Fig. 6 is a side elevation of an embodiment 30 of the invention differing somewhat from that illustrated in Fig. 1, and, Fig. 7 is a similar view of still another embodiment of the invention.

The object of the invention is to provide a simple convenient and economical rack adapted to be used in postal cars as mail pouch racks, the particular object of the invention being to provide a rack of this character which may be so placed as to conform 40 to the standard height above the floor of the car, which standard height is approximately three (3) feet, and which will leave sufficient clearance below the rack at the side of the car for a sufficient number of heating pipes to properly warm the car.

In addition to the foregoing, an equally, if not more important object of the invention is to furnish a construction whereby to reduce the heretofore unutilized space 50 between the adjacent ends of the rack sections, thus shortening the total space required for the row of racks without in any way reducing the net working space.

Heretofore racks have been commonly used in postal cars which are adapted to

be folded against the side walls of the car when not in use, but such racks have been found objectionable because of multiplicity of parts and lack of space below the same for heater pipes. Also, because these older 60 styles of racks, by reason of their structural formation required a substantial spacing apart, to overcome which is, as above suggested, one of the characteristics of the present invention. 65

I have overcome the objections to racks now in use in the present design, which comprises parts which may be readily attached in position to either steel or wood cars, as may be desired and which when not 70 in use as holding racks for pouches may be folded up against the sides of the car, as shown in dotted lines in Fig. 1.

Referring to the parts the line F indicates the inner face of the car wall, against 75 which is secured the bracket H which is preferably a casting, provided with suitable orifices for the passage therethrough of screws or bolts to secure the same in operative position,—the bracket H is provided 80 near its lower end with an offset portion G which is perforated for the passage therethrough of a suitable rivet to secure the brace I pivotally in position. F' represents the windows in said wall. Disposed at 85 a suitable distance apart in the bracket H are seats or recesses B and B', which seats or recesses are connected by a vertical passage S, the object of which will be herein-after more fully explained. 90

As will be observed in Fig. 2, the rack 1 comprises four rods 2, and 3, 3, 3, the rod 2 being held in the upper seat B of the bracket H and this rod as well as the rods 3 extending through or being connected 95 with side frame members 4 one at each end of said rods. It will be noted that the outermost rod 3 is in a plane below the next red 3 when rack 1 is in its relatively horizontal position, this being for the well understood purpose of connecting thereto the bag racks commonly used in postal cars. Each of the side frame members 4 is provided with a downwardly extending perforated lug 5, through which extends a suitable 105 pivot 6 which is adapted to connect the brace members I before referred to with said side frame members, and as the braces I are pivoted at 6 at their lower ends, it is evident that they are free to swing upon 110

their pivots, so as to permit changing position of the racks.

When the racks are in their horizontal position, as shown in full lines in Fig. 1, 5 the rods 2 will rest in a seat B at the upper end of the bracket H and the outer portion of the rack will be supported by the braces I, as shown in Fig. 2, but when it is desired to fold the rack all that is necessary 10 is to force the rod 2 inwardly sufficiently far to free it from its seat B whereupon said rod may drop downwardly along the passage S into the seat B' as shown in dotted lines in Fig. 1, and the rack will be 15 folded into the closed position shown in dotted lines in Fig. 1, the brace I swinging upon its pivots 6 during this movement and tending to draw downwardly the inner portion of said rack.

20 There is a desirable feature of the invention incident to the swinging of the racks upwardly into the approximately vertical position shown in Fig. 2, which should be here noted, the same being the fact that the 25 upwardly extending portions of the rack being in this position directly in front of the windows, they thus serve as a protection for the windows against storage matter, etc. When the rack is in its folded position and 30 it is desired to extend it to the horizontal position, this operation may be reversed.

The preferred arrangement is that illustrated in the first series of views of the drawings, special reference being made to 35 Figs. 4 and 5 wherein it will be seen that the bracket is provided with a single base portion and two closely associated guides for the frame members, the guides being separated a distance substantially that of the 40 combined width of a pair of adjoining frame members (Fig. 4). These frame members constitute the ends of separate sections and demonstrate the minimum amount of space required for assembling my improved racks together, substantially no excess or loss of space being encountered in such a construction.

50 It will be apparent that in lieu of the construction above defined the frame members may be provided at their ends with separated ears adapted to embrace the guide portions of the brackets and bring the main body portions of the frame members 4 in the plane of and directly in front of the 55 bracket to obviate the necessity of providing additional space at the sides of the bracket which would be necessary where the frame members are attached outside of the bracket as distinguished from being split 60 and embracing the bracket as here pointed out. It is believed unnecessary to illustrate this idea as it will be obvious to any one skilled in the art.

65 It is obvious that the racks 1 and brackets referred to may be so positioned that the

brackets may be located within the rack, Figs. 1, 2 and 3, that is between the side frame members 4 or the brackets H may be placed outside the said side frame members, in which latter case it may be desirable to provide rod 2 with collars 7 (Fig. 6), which will bear against the brackets H and prevent longitudinal shifting of the racks 1 in said brackets.

70 In the embodiment of the invention illustrated in Fig. 6, the lower portion of the bracket is devoid of the notch or seat utilized in that form of device illustrated in Fig. 1, and in lieu thereof a weighted gravity actuated dog J is provided, the same being adapted to automatically swing over the rod 2 when the rack is elevated and to be released by means of a finger piece J when the rack is to be opened.

75 In Fig. 7, I illustrate still another embodiment to emphasize the breadth of the invention. In this form the brace rod or strut is carried from the lower end of the bracket outwardly to the end of the frame member 4 rather than to the intermediate 80 point shown in the other forms. In the form now being considered I also provide a weighted gravity lock L near the upper end of the bracket adapted to engage the rod 2 when the rack is in open or extended 85 position.

90 In any or all of the embodiments of the invention herein disclosed the lower end G of the bracket to which the brace or strut is pivoted may be carried forwardly and downwardly to leave a space M therebehind 95 for the accommodation of the heating pipes.

95 What I claim is:

1. In a device of the character described, the combination comprising coupled brackets having alined rack seats in two planes, a 100 rockable rack and means holding the same against the top portion of the lower of said alined seats.

105 2. In a device of the character described, the combination comprising coupled brackets having alined rack seats in two planes, and a rockable rack adapted to engage either set of said alined seats, and auxiliary means for locking the rack in one of its positions.

110 3. In a device of the character described, the combination comprising coupled brackets having alined rack seats in two planes, and a rockable rack adapted to engage either set of said alined seats, and auxiliary means 115 for locking the rack in one of its positions comprising a weighted gravity actuated dog adapted to open to permit the rack to pass and to close to lock the rack in position.

120 4. In a device of the character described, a bracket, a rack having one end slidably mounted in said bracket and shiftable from one position to another relative to said bracket, means for holding said rack in one of the plurality of positions and means 125

adapted to lock said rack in said held position.

5. In a device of the character described, the combination of a bracket having a vertically disposed passage therein and a pair of seats or recesses offset from and communicating with opposite ends of said passage, a rack slidably mounted in said passage adapted to be pivotally mounted in said 10 seats or recesses, and a pair of locks one co-acting with each of said seats or recesses to hold the rack pivotally mounted therein.
6. In a device of the character described, the combination of a bracket having a vertically disposed passage therein and a recess communicating with said passage, a rack slidably mounted in said passage and recess 15

and a gravity lock co-acting with said recess automatically to lock said rack therein.

7. In a device of the character described, 20 the combination of a bracket, a rack adapted to be supported from said bracket when in extended position and adapted to be folded to a vertical position, means locking said rack in folded position and additional 25 means locking said rack in extended position.

In witness whereof I have hereunto set my hand in the presence of two witnesses:

VICTOR WILLOUGHBY
